LOCKER FOR A BICYCLE, MOTORCYCLE OR THE LIKE

Benjamin Agundez III, 5930 Franklin,
Los Angeles, Calif. 90028

Filed Oct. 29, 1974, Ser. No. 518,319

Term of patent 14 years

Int. Cl. D6—04

U.S. Cl. D6—181

FIG. 1.

FIG. 2.

FIG. 3.

FIG. 1 is a front, top and right side perspective view of a locker for a bicycle, motorcycle or the like showing my new design;

FIG. 2 is a rear, top and left side perspective view; and

FIG. 3 is a bottom plan view.

I claim:

The ornamental design for a locker for a bicycle, motorcycle or the like, substantially as shown.
